UNITED STATES PATENT OFFICE.

WILLIAM H. JOHNSON, OF RACINE, WISCONSIN.

ROLLING-DIE MACHINE.

SPECIFICATION forming part of Letters Patent No. 396,361, dated January 15, 1889.

Application filed April 27, 1888. Serial No. 272,076. (No model.)

To all whom it may concern:

Be it known that I, WILLIAM H. JOHNSON, of Racine, in the county of Racine and State of Wisconsin, have invented new and useful 5 Improvements in Rolling-Die Machines; and I do hereby declare the following to be a full, clear, and exact description of said invention, reference being had to the accompanying drawings, and to the letters or figures of reference marked thereon, which form a part of this specification.

My invention relates to improvements in rolling dies for cutting and compressing metal.

In the drawings, Figure 1 represents a side 15 view, and Fig. 2 a top view, of a die-machine containing my improved form of roller-dies. Fig. 3 represents a top view of one of the die-blocks removed from the machine. Figs. 4 and 5 represent several forms of dies made in 20 the interchangeable convex surfaces of the die or face blocks which are used for cutting or pressing out the various forms of metal. Fig. 6 represents an end view of the machine. Fig. 7 is a detail.

25 The mechanism by which my roller-dies are operated is represented in connection with a gang-punch with which it is adapted to be operated. The gang-punch mechanism does not, however, form any part of the present invention.

In the drawings like parts are represented by the same reference-letters throughout the several views.

The supporting-frame of the machine consists 35 of two longitudinal bed-plates, A A, supported on legs B B, and rigidly connected together by cross-pieces C. Projecting upwardly from and supported on the bed-plates A A are standards D D, in the top of which 40 the transverse driving-shaft E has its bearings.

F F are driving-pulleys.

G G are fly-wheels, and H H are pinions, all of which are fastened to the driving-shaft 45 E. The pinions H H mesh with the spur-wheels I I, which spur-wheels are loose on the transverse shaft J. Shaft J has its bearings on the standards D D. The hubs K K, integral with the spur-wheels I I, are provided with recesses a a and projections b b, alternately fitted and adapted to mesh with corresponding recesses, c c, and projections d

d on collars L L, which collars L are splined on the shaft J in the ordinary manner. The collars L L also have each an annular groove, 55 e, about them in their peripheries, in which the bifurcated ends of the levers M M operate. The levers M M are centrally pivoted on the top of the supporting-standards N, and at their ends opposite the grooved collar L 60 are pivoted to the outer ends, respectively, of the toggle-arms O O, which toggle-arms at their inner ends are pivoted to the horizontal endwise-moving rod P. The rod is supported and slides in the top of standard N, and standard N is supported rigidly on the frame of the machine. The rod P is provided with handles at both ends, whereby it may be actuated at either end of the machine. It will be understood that by moving the rod endwise 65 motion is communicated by and through the arms O O and levers M M to the collars L L, whereby said collars are thrown into and out of gear with the hubs K K, whereby the shaft J will be thrown in or out of gear with the 70 driving mechanism.

As shown upon the right in Figs. 1 and 2, the dies by which rods and bars of metal are pressed into the various shapes desired are connected with the shaft T by two cranks, 80 A' A', and two pitmen, B' B'. To the outward ends of the pitmen B' B' is pivoted a reciprocating cross-head, C', which is arranged transversely to and rests upon the bed-plates A A of the machine.

D' D' are the die-blocks, which are pivoted at their outer ends to the stationary plate E' upon the vertical trunnions F' F', which plate E' is arranged parallel to the cross-head C' and is rigidly affixed to the bed-plates A A. 90 The die-blocks D' D' are both in like manner connected at their inner opposing ends to the cross-head C' by the connecting links or bars G' G'. The bars G' G' are connected to the cross-head C' at equal distances from its center by pivots H' H', and to the blocks D' D' by pivots I' I'. Thus it is obvious that as the shaft T rotates a reciprocating motion is communicated therefrom, through the cranks A' A' and pitmen B' B', to the cross-head C', and from the cross-head C' an oscillating motion is communicated to the die-blocks D' D' through the links G' G'. 95 100

The die-blocks D' D' are each provided with

removable dies $J' J'$, having corresponding convexed surfaces which conform to a circle described around the supporting-pivots $F' F'$, respectively, whereby it is obvious that as 5 the dies turn on their respective supporting-pivots $F' F'$ their faces may be moved in contact or in close proximity to each other the entire length of their convex surfaces, whereby by the metal rods or bars introduced between 10 them are uniformly pressed by contact with their opposing convex surfaces. The dies of face-blocks $J' J'$ are bolted firmly to the die-blocks $D' D'$ by screws or bolts $K' K'$. The length of the bolts $K' K'$ is such as to permit 15 of a slight variation in the adjustment of the dies as may be required to make the two dies co-operate properly together, and in case the dies are adjusted out of contact with the blocks thin pieces of sheet-metal filling 20 may be interposed in the spaces between such parts.

To provide for pressing metal of varying thicknesses, the journal-bearing L' of one or both of the blocks D' may be made adjustable, as shown upon one side of the machine in Fig. 2 and in Fig. 3. When desirous to adjust the blocks D' farther apart, the adjusting-bolts $M' M'$ are turned outward, and one or more pieces of filling are inserted at a' between the journal L' and the cross-piece N' of the block, when the screws $M' M'$ are again turned down firmly in place against the journal-bearings. Thus by inserting or withdrawing the pieces of filling a nice adjustment 35 of the opposing surfaces of the dies may be attained. If desirous to simply flatten the metal or bars, die-blocks having plain surfaces are employed. If, however, any peculiar form of barb or point or other metallic 40 thing is desired, the dies are formed accordingly, as indicated in the four different forms of dies shown under Figs. 4 and 5.

$O' O'$ are adjusting-screws by which the position of the die-supporting blocks are adjusted. The screws $O' O'$ have screw-threaded bearings in the upward-projecting lugs $P' P'$ of the frame and bear at their inner ends against the opposing edge of the plate E' , whereby as the screws are turned inward or 45 outward the plate E' and the dies thereon are moved in either direction, as desired.

Having thus described my invention, what I claim as new, and desire to secure by Letters Patent, is—

55 1. In a die-machine, two segmental oscil-

lating die-blocks having opposing convex surfaces respectively pivoted to a stationary support, in combination with each other and with operating mechanism adapted to communicate an oscillating movement to both of said 60 dies simultaneously, substantially as and for the purpose specified.

2. The combination, in a die-machine, of two rolling die-blocks, $D' D'$, each provided with interchangeable adjustable face-blocks 65 $J' J'$, die-retaining pivots $F' F'$, connecting-links $G' G'$, head-block C' , pitmen $B' B'$, cranks $A' A'$, shaft T , and a chain of gears communicating therefrom with the driving mechanism, substantially as and for the purpose 70 specified.

3. The combination of the driving-shaft J , the thereon-revolving spur-wheels $I I$, provided with notched hubs $K K$, and the grooved collars $L L$, provided with teeth or lugs $d d$, 75 levers $M M$, centrally pivoted on standard N and provided with bifurcated ends riding in the grooves in collars $L L$, the toggle-arms $O O$, and reciprocating rod P , supported and riding in the top of standard N and provided 80 with handles, substantially as and for the purpose specified.

4. In the die-operating mechanism herein described, the combination of the shaft T , geared with the operating mechanism of the 85 machine, cranks $A' A'$, pitmen $B' B'$, reciprocating cross-head C' , connecting-links $G' G'$, communicating between the cross-head C' and the oscillating die-blocks $D' D'$, and the convex removable dies or face-blocks $J' J'$, 90 affixed to the opposing ends of the die-blocks $D' D'$, substantially as and for the purpose specified.

5. The combination of the shaft T , geared with the operating mechanism of the machine, 95 cranks $A' A'$, pitmen $B' B'$, cross-head C' , pivots $H' H'$, connecting-links $G' G'$, die-blocks $D' D'$, interchangeable die-blocks $J' J'$, having opposing convex surfaces connected with said blocks D' , and adjustable journal-bearings $L L$, secured in said die-blocks D' and adapted to operate on the die-supporting pivots $F' F'$, all substantially as and for the purpose specified.

In testimony whereof I affix my signature 105 in presence of two witnesses.

WILLIAM H. JOHNSON.
